UNITED STATES PATENT OFFICE.

EZRA T. WILLIAMS, OF CHICAGO, ILLINOIS.

FLUID-FUEL FEEDER.

SPECIFICATION forming part of Letters Patent No. 486,998, dated November 29, 1892.

Application filed June 5, 1891. Serial No. 395,255. (No model.)

To all whom it may concern:

Be it known that I, EZRA T. WILLIAMS, a citizen of the United States, residing at Chicago, in the county of Cook and State of Illinois, have invented a new and useful Improvement in Fluid-Fuel Feeders, of which the following is a full, clear, and exact specification.

My invention relates to devices of that class known as "injector-burners" for feeding fluid fuel, and has for its object to produce a feeder which shall thoroughly and effectually commingle the fuel fluids, converting them into a highly-inflammable gas; and to this end my invention consists in certain peculiarities of construction hereinafter described, but particularly pointed out in the claims.

In the drawings, Figure 1 is a longitudinal section. Fig. 2 is a cross-section on the line 2 of Fig. 1, and Fig. 3 is a cross-section on the line 3 3 of Fig. 1.

In the drawings, A is a valve-handle carrying the screw-threaded block B, which engages the screw-threads C of the pressure-fluid-discharging part G, the latter having a discharge-aperture provided with a valve-seat for the valve F, carried on rod R. The part G is cut away on its sides and bottom, so as to leave a partially-annular space around the solid portion N.

H is a stuffing-box for the valve-rod; J, a side aperture for the admission of a pressure fluid supplied through pipe J', controlled by valve J'. The nozzle L has a hollow body or case, which is threaded onto part G at K.

M M are screw-threaded nipples having supply-pipes M' with cocks M², constituting air-supply passages communicating with the nozzle back of the aperture in the pressure-fluid-discharging part G. The solid part N of the part G has a channel N', formed by the side ledges O O, which leads across the aperture controlled by the valve F.

S is a side lug on nozzle L, having a fuel-fluid-supply pipe S', a passage S² communicating with channel N', a valve S³, having a handle S⁴, and a graduated or other indicating scale S⁵, whereby the rate of the flow of oil to the burner may be indicated and regulated.

The use and operation of my device is as follows: The burner is adapted to be applied to all kinds of furnaces and is intended to be

used in the position shown in Fig. 1. The pressure-fluid—as, for example, steam—is admitted in suitable quantities through pipe J' and aperture J into the passage in part G, whence it is discharged, when the valve is withdrawn from its seat. The air, which is to be combined with the other fluids, is admitted through apertures M and fills the nozzle. The oil is fed down by gravity through the passage S² and into channel N', wherein it is confined by the ledges O and conducted to the aperture controlled by valve F, and through which aperture the pressure fluid escapes. The pressure fluid issuing from the aperture is intimately mixed or commingled with the oil in the channel and the air in the nozzle and the mixture carried out violently and discharged through the nozzle in the condition of a highly-inflammable gas. The proportions of oil, air, and steam are regulable.

The arrangement and proportion of the several parts may be modified without departing from the spirit of the invention, and I do not wish to be confined to the specific construction shown.

Obviously the pressure fluid may be compressed air, and the steam which is useful in atomizing the oil may be supplied through passages M. The making of the nozzle separate from the part G is for the sake of economy and because it is otherwise better construction. Obviously a diaphragm transversely dividing the nozzle and apertured for the passage of the pressure fluid and provided on its front side with a channel leading to said aperture, would utilize the principle of my invention, and the channel need not be vertical so long as it is adapted to convey the oil directly to the pressure-fluid aperture.

Having thus fully described my invention, what I claim as new, and desire to secure by Letters Patent, is—

1. In a fluid-fuel feeder, the combination, with a nozzle having a hollow case or body, of an interior pressure-fluid-discharging part cut away to provide a partially-annular space between it and the inner wall of the body of the nozzle, an air-supply opening into such annular space back of the fluid-pressure-discharge aperture, and an oil-supply way which leads through the wall of the case across the solid portion of the part through which the

pressure-fluid passes and to the fluid-pressure aperture, substantially as shown and described.

2. In a fluid-fuel feeder, the combination, 5 with a body having a discharge-nozzle, of an interior pressure-fluid-discharging part having an aperture opening interiorly of the nozzle, flanges or ribs on the pressure-fluid-discharging part partially surrounding said aperture, whereby there is provided a channel, and a fluid-fuel-supply way delivering into said channel, substantially as described.

3. In a fluid-fuel feeder, the combination, 15 with a discharging-nozzle, of a pressure-fluid-discharging part having a threaded connection with the nozzle, and said part having a

channel therein to receive the oil, said channel leading across the aperture for the discharge of the pressure-fluid, substantially as described.

4. In a fluid-fuel feeder, the combination, 20 with a discharge-nozzle, of an interior pressure-fluid-discharging part having a valve-controlled aperture for discharging the pressure-fluid within the nozzle, and an oil-supply way 25 leading to the aperture, substantially as described.
